H. S. CLARKE

STREET LIGHTING STANDARD

Filed Nov. 7, 1927

Harry S. Clarke.
INVENTOR.

BY *H. A. Preckman*
ATTORNEYS.

UNITED STATES PATENT OFFICE.

HARRY S. CLARKE, OF LONG BEACH, CALIFORNIA.

DESIGN FOR A STREET LIGHTING STANDARD.

Application filed November 7, 1927. Serial No. 24,032. Term of patent 3½ years.

To all whom it may concern:

Be it known that I, HARRY S. CLARKE, a citizen of the United States, residing at Long Beach, in the county of Los Angeles and State of California, have invented a new, original, and ornamental Design for a Street Lighting Standard, of which the following is a specification, reference being had

to the accompanying drawing, forming a part thereof.

The figure is a side elevation of the standard, showing my new design.

I claim:

The ornamental design for a street lighting standard, as shown.

HARRY S. CLARKE.
